METAL STRETCH BENDING APPARATUS

Raymond M. Ahonen, Southfield Township, Oakland County, Mich., assignor to Century Die & Manufacturing Company, Hazel Park, Mich., a copartnership of Michigan

Filed May 8, 1959, Ser. No. 811,885

10 Claims. (Cl. 153—40)

This invention relates to metal stretch bending apparatus and more particularly to apparatus for stretch bending a flat or semi-formed band or strip of metal into a curved molding about die forms arranged on complementary symmetrical mechanisms.

This application is a continuation in part of my earlier patent application Serial No. 630,164 filed December 24, 1956, issued as U.S. Patent No. 2,887,143 on May 19, 1959.

In general, the apparatus of this invention involves a split forming die of curved configuration to stretch bend a band or strip of metal into a curved molding piece, a pair of complementary die segments arranged for horizontal and vertical rotation, clamps associatedly conjoined with the die segments to hold the ends of the work piece upon the outer ends of the split die form, laterally sliding guided cam controlled plates upon which the die segments pivot for horizontal swinging movement, and vertical cams upon which the die segments ride during their period of vertical swinging. The die segments are pivotally mounted on horizontally rotatable plates or elements which are provided with cams adapted to bear upon base mounted cam followers, pivotally mounted in fixed positions upon a machine base intermediate the slides supporting the die segments. Power drive means is articulatedly connected to the plate members to rotate them and their cams against the cam followers, causing the slide supports to carry the horizontally rotating and vertically pivoting die segments into alignment at their inner ends as the work piece is stretched and bent about and upon the die form. By providing a vertical slide supported cam for one or both of the rotating die segments, the work piece, clamped at the outer ends of the die form sections, is caused to bend in a vertical path as well as in a horizontal plane, providing a compound curve in the molding. Such moldings are much used in automobiles about windshields and other window glass areas.

It is an object of the invention to provide in a metal stretch bending apparatus a pair of spaced apart, freely movable, sliding, guided, cam-controlled die segments arranged for horizontal rotation and vertical pivoting. Another object is to provide such die segments with strip holding clamps on the outer ends of the segments. A further object is to provide apparatus to stretch bend straight metal bands or strips. Yet another object is to provide vertical cams for the horizontally rotating die segments to cause them to pivot vertically.

These and other objects of the invention and features of construction will become more apparent from the description given below, in which the terms employed are used for purposes of description and not of limitation.

Reference is here made to the drawings annexed hereto and made an integral part hereof, in which

Fig. 1 is a top plan view of the apparatus of this invention, showing the complementary die segments in closed aligned position.

2

Fig. 2 is a top plan view of the machine of Fig. 1, showing the die segments in open position, the metal work piece being shown in broken lines, with the end clamps in open or retracted position.

5 Fig. 3 is a fragmentary enlarged front elevational view of the left hand side of the machine shown in Fig. 1, with parts broken away to show a portion of the apparatus below the top plate.

10 Fig. 4 is a horizontal sectional view, partially in plan, of the clamping mechanism associatedly conjoined with one of the die segments, the clamp being arranged in open position.

15 Fig. 5 is a view similar to Fig. 4 showing the clamping mechanism in closed position.

15 Fig. 6 is a fragmentary vertical sectional view taken substantially on the line 6—6 of Fig. 5.

Fig. 7 is a diagrammatic outline of the hydraulic system for the machine shown in Figs. 1-3 inclusive.

20 Fig. 8 is a perspective view of a finished molding produced by a machine of the type here disclosed, having a compound curvature developed by virtue of both horizontal rotation and vertical pivoting of the die segments.

25 The metal stretch bending machine or apparatus of this invention is generally symmetrical in character and arrangement and will be described as a double bend machine, i.e. a machine in which complementary die segments are actuated to form a metal strip or band into a finished molding of compound curvature.

30 As shown in the several views of the drawings, and particularly in Figs. 1-3 inclusive, the metal stretch bending machine 10 is arranged with a machine base 12 having a top plate base 14 to provide a suitable support for the stretch bending mechanism. On the top plate base 14 are two pairs of parallel slide guides or gibs 16, arranged in alignment and opposed to each other, in which the segmented stretch bending mechanism is slidably mounted. This mechanism comprises a pair of complementary die segments 18 and 20, right and left, respectively, slide plates or die support mounts 22 and 24 on which the die segments 18 and 20 are respectively horizontally pivotally mounted, clamping mechanisms 26 and 28 at the outer ends of the die segments 18 and 20 respectively, cams 30 and 32, right and left respectively, fixedly mounted on the die segment support plates 34 and 36, right and left respectively, and top plate base mounted cam rollers or followers 38 and 40, right and left respectively. A hydraulic drive system, designated generally by the reference numeral 42, Fig. 7, operates the mechanisms of the machine 10.

50 The machine base 12 is arranged with vertical walls or sides conjoined to the top plate base 14 to form a substantially box-type support. A hydraulic cylinder 44 is mounted upon the plate 14 rearwardly of the mechanism above described, and is of usual construction including an inlet conduit 46 at the rear end of the cylinder for hydraulic fluid to drive a piston 48 forwardly, and an inlet conduit 50 at the forward end of the cylinder for fluid to drive the piston 48 rearwardly. Piston rod 52, connected to piston 48, projects forwardly of the cylinder and supports a block member 56 which is adjustably mounted on the rod. Fixedly mounted on cylinder 44, and above it, is the limiting control valve 58 having a forwardly projecting valve control rod 60 which is operatively actuated by the block member 56 as the latter comes into contact with it.

55 The function of control valve 58 is to limit the return movement of the piston rod, due to inertial energy, which might cause the clamping mechanisms 26 and 28 to swing outwardly too far from the die segments 18 and 20, and to bring the clamping mechanisms and die segments into a positive predetermined starting relationship. The control valve 58 accomplishes this function by closing

off the hydraulic fluid in the system against entrance into the cylinder 44.

The elongated projecting piston rod 52 is arranged with a terminal cross member 62, which moves slidably on a supporting guide member 63 mounted on top plate 14 and projecting slightly forward of the machine base 12. Pivotally connected by yokes 64 to cross member 62 at either end thereof are a pair of adjustable links 65 having yokes 66 affixed at their opposite ends.

In view of the symmetry of the stretch bending machine or apparatus 10, it is deemed sufficient to describe in detail one of the two complementary portions of the mechanism, it being understood that the second portion is substantially identical in parts and conjoined arrangement except that the second portion is disposed in inverse relationship. The portion to be described in greater detail is located to the left of the piston rod 52, as shown particularly in Fig. 3.

As shown in Figs. 1-3 inclusive, the slide plate or die support mount 24 is slidably mounted in guides or gibbs 16, 16. Pivotally supported in a vertical bearing 68 on slide plate 24, is a hub 70 having a bearing flange 72 resting on the plate 24 and a sleeve 74 rotatable in bearing 68. The top plate 14 is cut out at 76 to allow for free oscillating lateral movement of the bearing 68 therethrough, permitting the bearing to project below the top plate, where a rod 80 is slidably mounted transversely on the lower end of the bearing. At the lower end of bearing 68 is a rod bearing block 82 having a bearing opening 84 through which the rod 80 is freely slideable. The complementary second portion bearing 68, fragmentarily shown at the right in Fig. 3, has fixedly connected thereto its rod bearing block 82 to support the right end of rod 80. Arranged outwardly of the two blocks 82 are compression springs 90 held in operative engagement by nuts 92 threaded onto the outer ends of rod 80.

The die segment support plate 36 is fixedly conjoined to the hub 70 and provides the mount for attachment below, in the same plane, or above, of the cam 32, and for attachment of the lever plate member 94 the inner end of which is pivotally linked at 96 to the yoke 66. Cam 32 is arranged to operatively bear on cam roller or follower 49 which is pivotally and rotatably mounted on pivot bearings 98 affixed to the top plate 14.

Surmounted on lever plate 94 is the die segment 20 embodying the die form of the configuration into which the metal strip is to be stretch bent, the outer end of the die segment being link connected to the band clamping mechanism 28. Affixed to the rearward edge of the die segment support plates 34 and 36 are the clamp limiting guides 100 and 102, respectively, which serve to limit the rotative movement of the clamp bearings at the stops 104 and 106, as shown in Figs. 1 and 2.

The clamping mechanisms 26 and 28 each comprise a hydraulic piston type cylinder 112 having a piston rod 114 projecting therefrom at the end of which is affixed the joint 116. Pivotally mounted at 118 on the end of the joint 116 is a bell crank 120 having a central pivot 122 and an end pivot 124 mounted in clamp housing 126. Linked at one end to pivot 122 is a lever 128 having a pivot 130 slidably mounted in upper and lower slots 132 arranged in the upper and lower walls 134 of housing 126. At the forward end of the housing 126 is a clamping bar or anvil 136, designed to close over the end of a metal band work piece laid upon the ends of the die segments 18 and 20. A linking member 138 is pivotally affixed at one end to the lever 128 by the pivot 130 and is positively and fixedly secured to the outer end of the die segments 18 and 20 as the case may be. The cylinder 112 is pivotally mounted at pin 146 by yoke 148 to a support block 150 which is fixedly mounted on the lever plate 94. A toggle break member 152 is embodied in a clamp housing 126 at the outer side thereof, comprising a tubular sleeve 154 closed at its outer end

and threaded exteriorly to screw into a threaded opening 156 in the housing 126, and a headed pin 158 slidably arranged within a coiled spring 160 disposed in the sleeve 154.

As shown in Figs. 1-3 and 8, the metal band 200, initially a substantially straight semi-formed strip having, as an example, only the cross-sectional contour shown in Fig. 6, is laid upon the ends of the die segments 18 and 20, ready for closing of the clamping bars 136. A transverse embossment 140 is provided on the end portion of the die segment in direct contact with the metal band 200. A complementary recess 142 is provided in the clamping bar or anvil 136.

The die segments 18 and 20 are arranged for vertical pivoting by means of a bearing block 162 fixedly mounted on each die segment, a bearing block 164 fixedly mounted on each die segment support plate 34 and 36, and a pivot pin 166 rotatably positioned in both blocks. Fixedly mounted on each slide plate 22 and 24 is a vertical cam 168 having the cam surface contour required for a particular application or part. A cam follower 170 is pivotally and rotatably mounted on each die segment 18 and 20 in a position to bear upon the vertical cam 168, so that as each die segment is rotatably pivoted on its bearing 68 the die segment will pivot in a vertical plane on the pivot pin 166 as the cam follower 170 rides upon the vertical cam 168. Although the vertical cams are shown positioned at the outer ends of the die segments 18 and 20, it will be understood that the cams 168 may be placed at other positions within the sweep of the die segments, the horizontal pivot pin 166 also being arranged in a different position, if necessary, to accommodate the requirements of a particular application or part.

The hydraulic system 42, shown diagrammatically in Fig. 7, comprises an electric motor 202 driving a pump 204 which feeds hydraulic fluid, preferably oil, through a pressure regulator valve 206, a check valve 208 to a four-way valve 210 whose component units are designed to pass fluid to the control valve 58 mounted on top of cylinder 44, and through this valve to the cylinder 44. Valve 210 also passes hydraulic fluid to the clamping cylinders 112 which operate the clamping mechanisms 126 and 128. A fluid supply tank 214 is provided in the base of the machine 10 for use by the pump 204 and for discharge of exhaust fluid from the valve 210.

The metal stretch bending machine 10 is operated by control switch mechanisms not shown. These switches may be of several types, the electrical push button being preferred. In each instance, an operation of the machine is accomplished by actuating a control device which causes a part or parts of the apparatus to function in accordance with its structure and organizational arrangement. To start the machine 10 the motor 202 is energized operating the hydraulic pump 204. In the open machine position shown in Fig. 3 a metal band work piece is laid upon the ends of the die segments 18 and 20 over the embossments 140. The clamping mechanisms 26 and 28 are closed over the ends of the work piece by operation of the control valve 210 which passes fluid to the clamping cylinders 112. When the clamps close over the ends of the band 200, the embossments 140 and the clamp bar recesses 142 grip the metal band firmly and positively prior to the stretch bending operation.

Valve 210 passes fluid to the control valve 58 which in turn passes it to the master cylinder 44, through inlet conduit 46, forcing piston rod 52 forward. As rod 52 moves forwardly, the die lever plates 94 are rotated by linkage 66, 65, 64 and 62 about their pivot bearings 68 until the inner ends of the die segments 18 and 20 come forward to a contiguous closed alignment, as shown in Fig. 1. As the die lever plates 94 rotate on their pivots 68, the band 200 is stretched between the ends of the die segments upon and by the complementary die forms on

the die segments which swing into closed alignment, Fig. 1, forming the band thereabout. The slide plates 22 and 24 freely slide laterally in the gibs 16 to allow for the stretch forming action of the die segments as the cams 30 and 32 bear against the table-fixed cam followers 38 and 40 respectively. The metal band 200 holds the two die units against their respective cam followers and toward each other.

When the band has been stretchformed to the die configuration, the control valve 210 is actuated to pass hydraulic fluid to the clamping cylinders 112 for reversal of the pistons and consequent opening of the clamping mechanisms 26 and 28. The finished stretch formed band 200, Fig. 8, is then removed from the die segments 18 and 20.

To return the die units to their initial starting positions, the control valve 210 is actuated to pass hydraulic fluid to the master cylinder 44 through the forward inlet conduit 50, reversing the movement of the piston rod 52, retracting it into the cylinder and swinging the inner ends of the die segments rearwardly toward the initial starting position shown in Fig. 2.

To avoid inertial uncontrolled movement past the desired starting point, the block member 56, fixedly mounted on the piston rod 52, makes engaging contact with the valve rod 60 to open valve 58 and release fluid to the master cylinder 44 whereby the piston therein comes to a positive stop. In this way the back sweep of the die segments does not override the initial starting position of the machine.

The die segments 18 and 20 are easily replaceable for the production of new and different metal band sizes and shapes without otherwise modifying the apparatus. In some instances, the die segments can be made with removable, replaceable and interchangeable die forms if such modifications are desirable and/or economically feasible. Such features are of importance from the standpoint of machine adaptability and range.

The vertical camming feature here disclosed provides a means for embodying compound curves in the metal molding through vertical pivoting associated with simultaneous horizontal swinging of the die segments. Although the die segments are shown arranged for vertical swinging on the pivot pins 166, the die segments may alternatively be arranged to pivot in a plane other than horizontal, as the particular application should require. This plane in any event will be normal to the axis of the pivot pin 166.

It will be understood from the foregoing description that the effective operation of the inventive apparatus here disclosed is based upon and is dependent upon the cooperative relationship of the die form on the die segments, the die segments and the cams which actuate the lateral sliding movement of the die supports and actuate the vertical swinging of the die segments.

Although the preferred means for driving the apparatuses here disclosed is an oil hydraulic system, it will be understood that other fluids, such as air or other gas, water, etc. may also be employed. Further, the drive means may be mechanical in nature, including gearing, levers, etc. If mechanical drive means are used suitable limit switches and electric brakes on the motor drive can be arranged without difficulty to meet the needs of the apparatuses. It will easily be understood by persons skilled in the art to which the invention pertains that the drive means may be varied substantially from that shown and described herein.

Although the vertical pivot means 162, 164 and 166, to permit vertical swinging of the die segments 18 and 20, is shown disposed transversely of the die segments of the drawings, this means can also be arranged so that it is parallel to the die segments, whereby the vertical swing of the die segments is toward and away from the front of the machine. Or, the pivoting of the die segments, in conjunction with the vertical cam means 168

and 170, can be arranged in any other suitable relationship and at any other suitable angle, as the particular job or work application may require.

The metal strip or band used with the apparatuses here shown and described is preferably longitudinally straight. In cross-section it may be contoured or straight depending upon the requirements of the application. In certain instances, a straight flat metal strip, of rectangular cross-section, may be stretched and bent into a curved form having a contoured cross-section, depending upon the cross-sectional nature of the die forms and the elements of longitudinal curvature in the die forms. The invention is not to be considered as solely limited to a metal strip having a contoured cross-section.

The principal advantages of the construction disclosed reside in the simplicity of the apparatus, the positive control of each stage of its operation, the broad scope in its stretch forming of intricate, complex forms as well as more simple metal forms, and the facile replacement features when die sizes and shapes are changed to produce new product sizes and forms.

Having described the invention in its simplest terms, it is to be clearly understood that the features of construction may be changed and varied in greater or lesser degree without departing from the essence of the invention.

I claim:

1. In apparatus for stretch bending metal strips or bands, a top plate base support, a pair of complementary, cam controlled, laterally movable, aligned die support mounts slidably arranged on said base support, guide means for each of said sliding die support mounts, each of said mounts having a die segment with metal strip die form thereon; a plate member horizontally rotatably mounted on each of said sliding mounts, each of said die segments being pivotally mounted for vertical swinging on each of said plate members, clamp means conjoined to the outer end of each die segment to releasably grip and hold said metal strip on said die forms adjacent the outer ends thereof, means to mount said die segments for horizontal rotatable movement, the inner ends of said die segments being free to swing into and out of alignment, horizontal cam means on each of said plate members rotatable therewith and means on said base support associated responsive to said cam means to laterally move said mounts in said guide means, vertical cam means on each of said die support mounts and means on each of said die segments associated responsive to said vertical cam means to pivot said die segments vertically as the latter rotate horizontally, and power drive means conjoined to said plate members rotatably moving said die segments and swinging the inner ends of said die segments in arcuate paths into contiguous alignment to a predetermined final position so as to stretch and bend said metal strip fully about and upon said die forms, said power drive means being operable through said horizontal cam means to control the movement of said die support mounts.

2. The construction defined in claim 1, and in which said vertical cam means on each of said die support mounts is arranged at the outer side edge of said mount.

3. The construction defined in claim 1, and in which said means associated responsive to said horizontal cam means comprises a cam follower rotatably mounted in fixed position on said base support.

4. In apparatus for stretch bending metal strips or bands, a base support, a pair of complementary, cam controlled, laterally movable, aligned die support mounts slidably arranged on said base support, guide means for each of said sliding die support mounts, each of said mounts having a horizontally rotatable plate member vertically pivoted on said mount and having a die segment with metal strip die form thereon pivotally mounted on said plate member for swinging in a plane other than horizontal, means to mount said die segments for horizontal rotatable movement, the inner ends of said die segments being free to swing into and out of alignment,

clamp means conjoined to the outer end of each die segment to releasably grip and hold said metal strip on said die form adjacent the outer end thereof, horizontal cam means on each of said plate members rotatable therewith and means on said base support associatedly responsive to said cam means to laterally move said mounts in said guide means, cam means on each of said die support mounts and means on each of said die segments associatedly responsive to said latter cam means to pivot said die segments in planes other than horizontal as said die segments rotate horizontally, and power drive means conjoined to said plate members rotatably moving said die segments and swinging the inner ends of said die segments in arcuate paths into contiguous alignment to a predetermined final position so as to stretch and bend said metal strip fully about and upon said die forms, said power drive means being operable through said horizontal cam means to control the movement of said die support mounts.

5. The construction defined in claim 4, and in which said cam means on each of said die support mounts is arranged vertically at the outer side edge of said mount.

6. The construction defined in claim 4, and in which said means associatedly responsive to said horizontal cam means comprises a cam follower rotatably mounted in fixed position on said base support.

7. In apparatus for stretch bending metal strips or bands, a base support, a pair of complementary, laterally movable, aligned die support mounts slidably arranged on said base support, guide means for each of said sliding die support mounts, each of said mounts having a die segment with metal strip die form thereon rotatably supported and pivoted on said mount for swinging in a plane other than horizontal, means to mount said die segments for rotatable movement, the inner ends of said die segments being free to swing into and out of alignment, clamp means conjoined to the outer end of each die segment to releasably grip and hold said metal strip on said die form adjacent the outer end thereof, cam means on each of said means mounting said die segments for rotatable movement rotatable therewith and means on said base support associatedly responsive to said cam means to laterally move said mounts in said guide means, cam means on each of said die support mounts and means on each of said die segments associatedly responsive to said latter cam means to pivot said die segments in planes other than horizontal as said die segments rotate horizontally, and power drive means conjoined to said plate members rotatably moving said die segments and swinging the inner ends of said die segments in arcuate paths into contiguous alignment to a predetermined final position so as to stretch and bend

5

said metal strip fully about and upon said die forms, said power drive means being operable through said horizontal cam means to control the movement of said die support mounts.

8. The construction defined in claim 7, and in which said cam means on each of said die support mounts is arranged vertically at the outer side edge of said mount.

9. The construction defined in claim 7, and in which said means associatedly responsive to said first cam means comprises a cam follower rotatably mounted in fixed position on said base support.

10. In apparatus for stretch bending metal strips or bands, a base support, a pair of complementary, cam controlled, laterally movable, aligned die support mounts slidably arranged on said base support, guide means for each of said sliding die support mounts, each of said mounts having a horizontally rotatable plate member vertically pivoted on said mount and having a die segment with metal strip die form thereon pivotally mounted on said plate member for swinging in a plane normal to the axis of the pivot, means to mount said die segments for horizontal rotatable movement, the inner ends of said die segments being free to swing into and out of alignment, clamp means conjoined to the outer end of each die segment to releasably grip and hold said metal strip on said die form adjacent the outer end thereof, horizontal cam means on each of said plate members rotatable therewith and means on said base support associatedly responsive to said cam means to laterally move said mounts in said guide means, cam means on each of said die support mounts and means on each of said die segments associatedly responsive to said latter cam means to pivot said die segments in planes normal to the axes of their pivots as said die segments rotate horizontally, and power drive means conjoined to said plate members rotatably moving said die segments and swinging the inner ends of said die segments in arcuate paths into contiguous alignment to a predetermined final position so as to stretch and bend said metal strip fully about and upon said die forms, said power drive means being operable through said horizontal cam means to control the movement of said die support mounts.
